CLAIM

The ornamental design for a loudspeaker, as shown and described.

DESCRIPTION

FIG. 1 is a left side view of a loudspeaker in accordance with our new design;

FIG. 2 is a bottom plan view thereof;

FIG. 3 is a front view thereof;

FIG. 4 is a right side view thereof;

FIG. 5 is a top perspective view thereof;

FIG. 6 is a top plan view thereof; and,

FIG. 7 is a back view thereof.

The dashed broken lines in the figures depict portions of the loudspeaker that form no part of the claimed design.
